UNITED STATES PATENT OFFICE.

WILLIAM SHAKESPEARE, JR., AND WILLIAM SCHMID, OF KALAMAZOO, MICHIGAN,
ASSIGNORS TO WILLIAM SHAKESPEARE, JR., CO., OF KALAMAZOO, MICHIGAN.

CARBURETER.

1,179,664.

Specification of Letters Patent. Patented Apr. 18, 1916.

Original application filed December 16, 1912, Serial No. 736,996. Divided and this application filed June 13, 1913. Serial No. 773,412.

To all whom it may concern:

Be it known that we, WILLIAM SHAKESPEARE, Jr., and WILLIAM SCHMID, citizens of the United States, residing at Kalamazoo, Michigan, have invented certain new and useful Improvements in Carbureters, of which the following is a specification.

This invention relates to improvements in carbureters.

10 Our improvements relate particularly to the carbureter shown in our application for Letters Patent, Serial Number 736,996, filed December 16, 1912, the present application being a division of that application.

15 The main objects of this invention are: First, to provide in a carbureter, an improved means of supplying fuel for priming and starting the engine. Second, to provide an improved carbureter which may be adjusted for different temperatures, so that the air supply is kept at approximately the temperature desired.

20 Further objects, and objects relating to structural details, will definitely appear 25 from the detailed description to follow.

We accomplish the objects of our invention by the devices and means described in the following specification.

The invention is clearly defined and 30 pointed out in the claims.

A structure which is a preferred embodiment of our invention is clearly illustrated in the accompanying drawing forming a part of this specification, in which:

35 Figure I is a side elevation of our improved carbureter, the starting valve and air valve operating mechanism being shown in front elevation. Fig. II is a detail vertical section on a line corresponding to the

40 broken line 2—2 of Fig. I, the various parts not especially related to the features of this application being omitted. Fig. III is a detail bottom view of the valve stem 34 and its actuating means. Fig. IV is an end view

45 of the air supply conduit and the inlet valve thereof. Fig. V is a vertical section through the air supply conduit of the carbureter and its valve, on a line corresponding to line 5—5 of Fig. I. Fig. VI is a

50 front elevation of the primer and temperature control mechanism, with the index plate 22 removed. Fig. VII is a detail

vertical section on a line corresponding to line 7—7 of Fig. I.

In the drawing similar reference characters refer to similar parts throughout the several views, and the sectional views are taken looking in the direction of the little arrows at the ends of the section lines.

Referring to the drawing, the carbureter 60 body 1 is provided with an inlet passage or conduit 2 and a discharge passage 3 leading from the mixing chamber 4 above the valve seat 5.

The fuel nozzle and the air and fuel 65 valves are not shown as they form no part of this invention. The form preferred by us is shown and described in detail in our application for Letters Patent above referred to.

To control the temperature of the air passing to the carbureter, the conduit 2 is provided with a cold air inlet 6 and a heated air inlet 7 adapted to be connected to a suitable source of supply, as a coil 75 (not shown) heated by the exhaust. The cold air inlet and the heated air inlet are both controlled by the cylindrical valve 8 having a transverse port 9 of such length that the valve may be adjusted to admit 80 both cold and heated air in varying proportions or to shut off the cold air or the heated air entirely and take only cold or heated air. When the valve is adjusted so that the end 10 of its port strikes the stop 85 11, heated air only is admitted. When it is adjusted so that the end 12 of its port strikes the stop 13, cold air only is admitted. See Fig. V.

The valve 8 is controlled by the lever 14 90 arranged in a convenient position, as upon the dash 15 of a motor car, when our improved carbureter is used on a motor car engine. The lever 14 is provided with a sleeve-like bearing member 16 arranged 95 through the bearing 17 of the support 18 which is mounted on the front of the dash, the bearing 17 being arranged through the dash. On the rear of the lever bearing 16 is an arm 19 which is connected by the link 20 to the arm 21 on the valve 8. A dial plate 22 having suitable temperature indicia, as shown in Fig. I, is mounted on the support 18. The edge of the dial is 100

notched at 23, the notches and temperature indicia being uniformly spaced. The lever 14 is provided with spring pressed pawl 24 adapted to engage the notches for retaining the lever in its adjusted positions. The lever finger piece 25 constitutes an index.

The numerals of the index dial indicate the position the lever should be adjusted to for different atmospheric temperatures. 10 For instance, the lever 14 is shown adjusted to 40° and the air inlet valve is opened to take heated and cold air, approximately half and half. In a temperature of 80°, the lever would be adjusted to 80, at which point the 15 heated air inlet would be entirely closed. At a temperature of zero, the greater portion of air taken would be through the heated air port. At ten below zero, only heated air would be taken. This is found to be a very 20 advantageous feature in the proper control and regulation of the carbureter.

The primer valve 26 is arranged in a valve chamber 27 provided therefor above the fuel reservoir 28. The chamber 27 is 25 preferably formed in the wall of the carbureter body, the valve seat 29 being formed in the wall of the body at the inner end of the chamber, as clearly shown in Fig. II. The valve chamber 27 is connected to the fuel 30 reservoir 28 by the tube 30 depending into the reservoir. The valve 26 is held yieldingly in its seat by means of the coiled spring 31, one end of which bears against the collar 32 on the valve stem, the other being 35 seated in the closure 33 for the outer end of the chamber 27. The valve stem 34 projects through this closure and is provided with a disk-like head 35 with which the eccentric pin 36 on the rotating valve actuating member 37 coacts. The valve actuating member 37 is supported in a bearing 38 carried by the closure member 33. The actuating member 37 is connected by the 40 flexible shaft 39 to the spindle 40 of the lever 41, the spindle 40 being journaled in the sleeve-like bearing 16 of the lever 14.

The lever 41 is provided with a lug 42 coacting with the lug 43 on the lever 14. These lugs engage when the levers are swung to 50 certain positions. For instance, when the primer control is adjusted to start the engine at 10° temperature, the air control is shifted at the same time to the 10° position if it has not been previously adjusted to such 55 position. The primer control lever may, however, be returned to its running position without moving the air control lever. When the lever 14 is swung against the boss-like stop 44, this also swings the lever 41 against 60 the stop 45 or to its closed or running position. By this arrangement a very effective priming is secured which greatly facilitates starting of the engine. Further, if the primer be opened during the last few strokes 65 of the engine when stopping the same, the

cylinders will receive such a charge of fuel that the engine can be usually started from the spark, even for a considerable period after stopping.

In certain embodiments, the primer is 70 connected to a source of fuel supply independent of the regular fuel supply reservoir 28 which permits the use of high test or high grade hydro-carbon for starting, and of lower test fuel for the regular running. This merely necessitates the providing of a suitable reservoir of the high grade fuel and connecting the primer valve there-to instead of the reservoir 28. As such an arrangement will be readily understood, we 75 80 have not deemed it necessary to illustrate the same herein.

We have illustrated and described our improvements in detail in the highly satisfactory embodiment in which we have placed 85 the same upon the market.

While we are aware that various modifications in structural details are possible without departing from our invention, we believe that the disclosure made will enable those 90 skilled in the art to which our invention relates to embody the same as conditions may require and have not, therefore, shown or described such modifications herein. We desire, however, to be understood as claiming 95 our improvements specifically in the form illustrated as well as broadly within the scope of the appended claims.

Having thus described our invention, what we claim is new and desire to secure 100 by Letters Patent is:

1. A carbureter provided with a hot air inlet and a cold air inlet; a common valve for said inlets adjustable to admit cold air or hot air or both simultaneously; operating 105 means for said valve including a lever; a fuel valve; operating means therefor including a lever; an indicia dial associated with said levers and provided with indicia indicating temperature, the indicia for the 110 two levers being disposed so that the levers are moved in the same direction to bring them to zero; and coacting stops on said levers whereby the air valve control lever may be actuated when the fuel control lever 115 is operated to open the fuel valve and said fuel valve control lever may be actuated toward its closed position when said air valve control lever is actuated to close the hot air inlet.

2. A carbureter provided with a hot air inlet and a cold air inlet, a common valve for said inlets adjustable to admit cold air or hot air or both simultaneously, operating means for said air valve including a pivotally mounted lever, a fuel valve, operating means for said fuel valve including a pivotally mounted lever having its axis coinciding with the axis of said air valve operating lever, an indicia dial associated with said 120 125 130

levers and provided with indicia indicating temperature, the indicia for the two levers being disposed so that the levers are moved in the same direction to bring them to zero, 5 and coengaging parts on said levers adapted to engage when the levers are in certain adjusted positions.

3. In a carbureter, the combination of an air valve for controlling the air passing to the carbureter, operating means for said air valve including a pivotally mounted lever, a fuel valve, operating means therefor including a pivotally mounted lever, the axes of said levers being disposed to coincide, and 15 coengaging parts on said levers adapted to engage when the levers are thrown to certain positions, whereby the movement of one lever is imparted to the other.

4. In a carbureter, the combination of an air valve, operating means for said air valve including a lever, a fuel valve, operating means therefor including a lever, and coengaging parts on said levers disposed so that the engaging part of the fuel valve 25 lever is out of operative position when the fuel valve is closed.

5. In a carbureter, the combination with a needle valve, a spring for holding said valve normally seated, means for opening 30 said valve comprising a spindle having an eccentric pin thereon coacting with a head on said valve, means for rotating said spindle comprising a flexible shaft and a pivoted lever, and an indicia member associated with 35 said lever and having indicia thereon indicating temperature.

6. In a carbureter, the combination of a valve for regulating the temperature of the air passing to the carbureter, operating 40 means for said air valve including a lever, a fuel valve, operating means for said fuel valve including a lever, said levers being

mounted to rotate about the same axis, said levers being arranged to swing in oppositely disposed arcs and being provided with coengaging parts adapted to engage when the levers are in their normally closed position, the air valve lever being movable from its closed position without imparting its movement to said fuel valve lever. 45

7. In a carbureter, the combination of a valve for regulating the temperature of the air passing to the carbureter, operating means for said valve including a lever, a fuel valve, operating means therefor comprising a lever, an indicia dial associated with the said levers and provided with indicia for both levers indicating temperatures, the indicia for the two levers being disposed so that the levers are moved in the 60 same direction to bring them to zero, coengaging parts on said levers arranged so as to be brought into engagement by the swinging of the fuel valve lever toward and the air valve from its zero position. 65

8. A carbureter provided with an air regulating valve, a fuel valve, means for actuating said air valve including levers and coengaging parts on said levers adapted to be brought into engagement by the swinging 70 of the levers in opposite directions, whereby the levers are simultaneously adjusted when said parts are in engagement and are capable of independent adjustment when said parts are out of engagement. 75

In witness whereof, we have hereunto set our hands and seals in the presence of two witnesses.
